ANIMATED ADVERTISING DEVICE

William F. Currie, Chicago, Ill., assignor to Gale and Pietsch, Inc., Chicago, Ill., a corporation of Illinois

Application July 25, 1936, Serial No. 92,680

8 Claims. (Cl. 40—138)

This invention relates to an improved animated advertising device particularly adapted for use in public passenger vehicles, such as trains, street cars and busses, and which is designed to be actuated by the motion or vibration of the vehicle.

An object of this invention is to provide a means for lending animation to the usual advertising card which is customarily mounted against the interior side walls of a vehicle adjacent the top thereof, and may be readily applied to a completed sign already in use, so that the sign may be used with or without my device.

A further object of my invention is to provide an animated sign wherein the moving portion may be secured to the background in a fixed relation to it, and will rotate in an arc on a fixed axis, and which will not become displaced out of its desired or predetermined position in relation to the background.

Advertising cards for use in the interior of vehicles, to which this invention relates in particular, are usually mounted in a series adjacent the upper portion of the vehicle, and many of such vehicles are so constructed that their sides curve inwardly to meet the ceiling, so that the cards are mounted on a concave surface. An object of this invention is to provide a means for spacing the moving portion from the background by adjustable means, so that the portion providing animation will at all times move freely without interference due to the curvature of the background card.

Other objects relate to various features of construction and arrangement of parts which will be apparent from a consideration of the following specification and accompanying drawing, wherein:

Figure 1 is a perspective view of the interior of a vehicle showing the portion on which advertising cards are most commonly mounted, and further illustrates the curvature of the vehicle at this point, with a series of animated cards mounted in place.

Figure 2 is a front elevation of an advertising card illustrating animation.

Figure 3 is a detail of the moving object.

Figure 4 is a sectional view of Figure 2, on the line 2—2.

Figure 5 is a detail of the assembled operating connections and mechanism.

Figure 6 is a detail of the animation control spring and mounting stud.

Figure 7 is a detail of an optional rivet for securing one end of the spring to the moving object.

Figure 8 is a detail of the adjustable screw which holds and carries the moving object.

In the drawing 10 indicates an advertising card which may be mounted against a surface in the interior of a vehicle, as shown in Figure 1. Cards 5 of this kind usually carry reading matter accompanied by an illustration, as at 11, part of which may be animated, as for example the arm 12. In the preferred form of my invention I use a card on which the illustration is complete and use a 10 replica of a portion thereof, as shown by Figure 3, for the purpose of animation. However, my invention is not restricted to this manner of use, and the animated portion may be used to complete the illustration. 15

Between the background card and the object to be animated extends the internally threaded stud 13 which receives the screw 14. In the preferred form of my invention the stud and screw are provided with large heads and extend through suitable mounting tabs 15 and 16. Surrounding the stud and screw is a coiled spring 17 of a predetermined tension suitable for the object to be animated. One end of the spring is secured adjacent the head of the stud 13, preferably as 20 shown at 18, or in any other suitable manner. The opposite end of the spring which extends outwardly away from the center may be secured to the tab 16 at some suitable point as at 19, by means of the rivet 20, or in any other suitable 25 manner. This assembled structure forms a complete unit, and the object to be animated is secured to the tab 16, and the whole is then secured to the background by means of the tab 15 at the desired point to complete the illustration, or to 30 add the animated feature by superimposing it over its complementary portion. It may be readily seen that the tabs 15 and 16 need not be used, and instead the stud, screw and spring may be directly attached to the background and object, 35 however, I prefer to use the form shown so that metal parts are concealed and additional strength given to the assembly.

As stated in the objects of this invention, these advertising cards are very often mounted on 45 curved surfaces, as shown in Figure 1, at which time the card assumes the curved outline as shown dotted in the side view in Figure 4. In order for the object to swing freely it is necessary that it be set away from the background to provide 50 clearance. This is accomplished by means of the stud 13 and screw 12, which may be adjusted to each other prior to affixing the spring 17 to the point adjacent the head of the stud. It will thus be seen that the stud 13 acts as a means for ad- 55

justment and also as a bearing for the screw 14. This feature provides for great economy and adaptability of a single unit system for providing animation for cards that may be flat, or which 5 have varying degrees of curvature, either transversely or longitudinally. It will also be seen that by means of my assembled system the object to be animated will be held on a fixed axis or pivot about which it may swing in conformity 10 with the tension of the spring; the tension of the spring being generally determined by the size or weight of the object to be oscillated and the degree of arc it is desired to pass.

It is of course understood that motion or 15 animation is imparted to the device when mounted on the sides of the vehicle, by longitudinal movement or vibration thereof, and when the cards are mounted in the end portions of the vehicle they receive, in the main, impulses from 20 lateral movement. However, in a moving vehicle there is generally sufficient motion or vibration to operate the device when mounted at any point.

Although I have shown and described certain 25 features of my improvements for the purpose of illustration, it will be apparent to one skilled in the art that various changes may be made in the details and form of construction without departing from the spirit of my invention, and therefore, I do not wish to be restricted specifically thereto except as so limited by the appended 30 claims.

What I claim is:

1. In a device of the class described, a background member, a movable element positioned on said background by a pivot, a spring extending from the background to said element and adapted to impart motion to it, and means for longitudinally adjusting said pivot whereby the 40 spacing between the background and movable element may be varied.

2. In a device of the class described, a background member being normally flat and adapted to be positioned parallel with a concave surface, 45 a movable element positioned on said background by a pivot, a spring extending from said background to said element and adapted to impart motion to said element, and means for longitudinally adjusting said pivot whereby the spacing 50 between the background and movable element may be varied.

3. In a device of the class described, a background member, an element positioned on said background by pivot means, and a spring adapted 55 to impart oscillatory motion to said element in an arc about said pivot means, said pivot means comprising a bearing stud affixed to said back-

ground and a pivot affixed to said element and extending into said bearing stud.

4. In a device of the class described, a background member, an element positioned on said background by longitudinally adjustable pivot 5 means, and a spring adapted to impart oscillatory motion to said element in an arc about said pivot means, said pivot means comprising an internally threaded stud affixed to said background and a pivot screw affixed to said element 10 and extending into said stud.

5. In a device of the class described, a background member, an element positioned on said background and spaced therefrom by longitudinally adjustable pivot means, and a coiled 15 spring adapted to impart oscillatory motion to said element, said pivot means comprising a fixed bearing and carrying a longitudinally adjustable pivot.

6. In a device of the class described, a background member being normally flat and adapted to be positioned parallel to a concave surface, a bearing member extending out on an axis from said background and carrying a pivot, a movable element secured to said pivot, a spring extending 25 between said background and said movable element and adapted to impart oscillatory motion in an arc, said pivot being longitudinally adjustable in said bearing member to space said movable element from said background and to 30 allow said element to oscillate freely.

7. In a device of the class described, a fixed background member, an element adapted to lend animation thereto, and actuating means comprising a bearing stud extending axially from a mounting base secured to said background, a pivot extending into said stud and carrying a mounting base secured to said element, a spring extending from said stud to the mounting base of the pivot and secured thereto at a point away 40 from its center.

8. In a device of the class described, a fixed background member being normally flat and adapted to be mounted against and conform to the contour of a concave mounting surface, an element adapted to lend animation thereto by oscillating in arc on an axis extending from said background, an internally threaded bearing stud extending axially from a mounting base and affixed to said background, a screw pivot extending 50 into said stud and carrying a mounting base secured to said element whereby the element may be spaced from the background and oscillate freely in relation thereto, and a coiled spring having its inner end secured to the stud and its outer end secured to the pivot mounting base.

WILLIAM F. CURRIE.
